Specification for Design.

Patented Apr. 22, 1919.

Application filed March 14, 1919. Serial No. 282,754. Term of patent 7 years.

To all whom it may concern:

Be it known that we, ANGUS S. MACDONALD, of Great Neck Station, county of Nassau, and State of New York, and ALFRED W. PRESSEY, of 47 Lexington avenue, New York city, county of New York, and State of New York, have invented a new, original, and ornamental Design for Lamps, of which the following is a specification, reference being had to the accompanying drawing, forming a part thereof.

The figure is a side elevation of a lamp showing our new design, from inspection of

which it will be seen that the same comprises a lamp stand or shaft composed of a shell or portion of a shell, provided at the top with a lamp, and a shade therefor, having a profile substantially corresponding to that of a helmet.

We claim:

The ornamental design for a lamp as shown and described.

In testimony whereof we have hereunto signed our names.

ANGUS S. MACDONALD.
ALFRED W. PRESSEY.
